BEAT OSCILLATOR

Ilia E. Mouromtseff, Montclair, and George M. Dinnick, Bloomfield, N. J., assignors to Westinghouse Electric Corporation, East Pittsburgh, Pa., a corporation of Pennsylvania

Application July 18, 1941, Serial No. 402,958

19 Claims. (Cl. 315—38)

1

This application is a continuation-in-part of our copending application Ser. No. 360,367, filed October 9, 1940, for an Ultra-high frequency oscillator Patent No. 2,283,895 granted May 19, 1942.

Our invention relates to discharge devices, and especially to ultra-high frequency oscillators.

An object of our invention is to produce an ultra-high frequency oscillator having a high efficiency and a greater power output.

Another object of our invention is to provide an oscillator producing a powerful and stable "beat" wave.

A still further object of our invention is to provide an oscillating tube, utilizing a plurality of high frequency circuits within a common envelope.

Other objects and advantages of the invention will be apparent from the following description and drawing in which:

The figure is a view principally in cross section, of a discharge device embodying our invention.

In our copending application Serial No. 360,367, filed October 9, 1940, for "Ultra-high frequency oscillator," we have disclosed in Figure 5 two hollow body resonators each formed of a grid enclosing a cathode and a third resonator enclosing an anode.

Our present invention is to utilize different frequencies in the first two hollow body resonators, but to form the third hollow body resonator as a complete operating unit responding to the two frequencies and having an output circuit producing a powerful and stable "beat" wave from the two frequencies.

It is apparent, of course, that the structure disclosed in Figure 5 of our copending application could be utilized for this purpose by making a connection between the anode and the enclosing hollow body resonator and applying different frequencies to the grid-cathode resonators. In this application, however, we have disclosed in the figure, the hollow body resonator 22 as a unit with the interior portions thereof comprising a hollow pipe 10 with closed ends 11 and 12 acting as collector surfaces for the electrons.

The hollow pipe 10 has a side opening 13, to which is attached an integral or welded pipe 14, for the entrance of a cooling fluid to the interior of this hollow pipe 10. This pipe is preferably longitudinally divided by a plate 15 having a central opening 16 to which is attached an inlet pipe 17 for the cooling fluid. The divided plate

2

15 has openings 18 at either end for the cooling fluid, such as water, to flow around and out the pipe 14. The pipe 14 is welded at 19 to the hollow body resonator 22.

5 The hollow body resonator 22 is substantially symmetrical about the hollow pipe 10, and preferably has an end 23 parallel and slightly spaced from the collector face 11 and another end 24 parallel to and slightly spaced from the other collector face 12. Both ends 23 and 24 are perforated at 25 and 26 for the passage of electrons to the collector faces. The perforated ends 23 and 24 are thin and flexible so that their spacing from the collector faces may be easily adjusted.

10 Such an adjustment may be by a plate 27, welded to the outer portion of the end 23, and having therethrough adjusting bolts 28, secured to another plate 29, in turn screwed to the main portion of the hollow body resonator 22. A similar adjustment arrangement 27', 28' and 29' is located at the other end of the tube to adjust the end 24 in relationship to the collector face 12.

15 We preferably attach to the plate 27, a re-entrant insulating portion 70 and 70'. This insulating structure is sealed to a metal tube 71, welded to a tubular metal casing 72. The inner end of this tubular metal casing, has a perforated control grid structure 73, spaced in parallel to the perforated openings 25, in the adjacent end 23 of the hollow body resonator. The other outer end of the tubular casing 72, is preferably closed by flexible metal sheet 74, whose position can be adjusted by any suitable means as by the screw disclosed.

20 25 The cathode 75 comprises a thin plate of metal, bent to form a flat face parallel with the grid opening 73. This flat face has preferably longitudinal slots extending across the face of the cathode. These slots reduce the cross sectional area of the front face of the cathode, and the increased resistance causes the slotted portions of the cathode to rise to the desired temperature to produce electrons from the front face of the cathodes. Other types of cathodes may be used 25 if desired, such as the coated, indirectly heated, resistance wires, etc.

25 30 The ends of the cathode structure are attached to two rods 76 and 77, which extend to the outer end of the tube 72, and on their ends are preferably two metal pieces 78 and 79, spaced from the flexible end plate 74, a distance approximating the distance of the cathode 75 from the control grid 73. Spacing of this flexible end plate 74 from these two pieces of metal 78 and 55 79, is adjusted to produce capacitance therebe-

tween, equivalent to the capacitance between the control grid 73 and the cathode 75.

The cathode connections 89 and 81 are taken off through insulation 82, and a side tube 83. These cathode connections are preferably connected through a transformer 100 to a suitable source of cathode heating current 102. The cathode operating potential is derived from a source 101 and we prefer to make this source a highly negative voltage, for instance -10,000 volts with the positive end grounded. The hollow tube 72, forming the grid connection, has a connection in turn to a source of voltage 103, whose positive side is connected to the cathode connection as illustrated at 104. The value of the grid voltage may be in the neighborhood of -1000 volts.

The hollow tube 72 has a loop 84, preferably located at a central portion, and this loop has one end passing axially through insulation 85, and a short pipe 86, and both of these are connected to form another loop 87. The cathode and control grid on the opposite side of the hollow body resonator 22 are preferably similarly constructed and have corresponding parts designated with prime numbers including an external loop 87'.

We provide the central portion of the hollow body resonator 22 with a pipe 50 and attached to the inner surface of the hollow body resonator at the edge of this pipe, a conductor forming a loop 52 to enclose electromagnetic lines of force therein, and having its other end 51 passing axially through the pipe and a closed insulation block 53 to form an exterior transmission line.

The hollow body resonator 22 is grounded as indicated at 105. If desired, energy may be fed back from the hollow body resonator 22 to the grid-cathode resonators as described in our copending application Ser. No. 360,367, filed October 9, 1940, for an ultra-high frequency oscillator.

We preferably utilize the two exterior loops 87, 87' to feed slightly different high frequencies into the two grid-cathode hollow body resonators. Any suitable high frequency circuit, diagrammatically illustrated on the drawing as U. H. F. #1, may be tuned to a frequency of 700 megacycles per second for example, and feeds this frequency into the resonator 72 by means of a transmission line 120 having a loop 121 coupled to the loop 87. A second high frequency circuit, diagrammatically illustrated in the drawing as U. H. F. #2 may be tuned to a slightly different frequency such as 690 megacycles per second. Other variations in frequency of the order of 10^8 cycles may be used to advantage with this arrangement. This energy is applied to the loop 87' of resonator 72' through the transmission line 122 and loop 123. The openings 25 and 26 of the central resonator 22 are adjusted to receive the two frequencies.

The output circuit of the central resonator, namely, the conductor 51 and the eyelet 50 are connected to two transmission lines 124 and 125 in parallel. Transmission line 124 has an effective length equal to half the wave-length of U. H. F. circuit #1 and terminates at the loop 126. Transmission line 125 has an effective length equal to half the wave length of the U. H. F. circuit #2 and terminates in the loop 127. Both loops 126 and 127 are coupled to a circuit resonant to a frequency equal to the difference of the two original frequencies. It may consist of lump inductance 128 and capacitance 129 as shown or may be of any other suitable

type circuit. In the example given, this would be 10 megacycles per second. The two frequencies would produce a powerful "beat" wave in the output portion 130 of this resonant circuit.

Attention is also directed to the fact that our grid and cathode construction makes a radio frequency voltage between the grid and cathode readily available and in fact, this construction is equivalent to a voltage transformer.

10 We have designed our grid and enclosed cathode to resonate to a desired frequency and this frequency is the frequency or approximately the frequency utilized in the main resonator 22. The capacity between the elongated cathode structure of the cathode proper 75, rods 76, 77, metal pieces 78, 79 and the elongated enclosing grid structure 72 is longitudinally distributed. The capacity between the cathode proper 75 and the grid proper 73 is lumped and is balanced 20 at the other end by lumped capacity between the metal pieces 78, 79 and the adjustable end plate 74. The resonator 72 (and similarly the resonator 72') has a capacity that is symmetrical both in radial and longitudinal directions. The 25 linear rods 76, 77 extending substantially along the axial portion of the enclosing cylindrical grid structure forms a concentric line cavity resonator. The feed-back of a necessary amount of energy from the main resonator 22, as shown in 30 our copending application Ser. No. 360,367, will cause the resonance of the grid structure 72 at the desired frequency. The specially designed and adjustable resonance of the grid resonator 72 will cause the operation thereof at a minimum 35 loss of energy in the resonator itself. The resonator has a relatively high Q.

Although we have shown and described a specific embodiment of our invention, we do not desire to be limited thereto, as various other 40 modifications of the same may be made without departing from the spirit and scope of the appended claims.

We claim:

1. A discharge device including a hollow body 45 resonator and means physically opposed to each other on opposite sides of the resonator for applying two different frequencies to said hollow body resonator.
2. A discharge device including a hollow body 50 resonator the body whereof provides a resonator chamber having openings common to the one chamber for the passage of electrons therethrough directly into said chamber at two different portions thereof, and two current means at different frequencies for passing electrons through 55 said openings.
3. A discharge device including a hollow body resonator the body whereof provides a resonator chamber having openings common to the one 60 chamber for the passage of electrons therethrough directly into said chamber at two different portions thereof, cathode means for supplying electrons to and through the openings at one portion, cathode means for supplying electrons to and through the opening at the other portion, a 65 circuit means modulating one electron stream, another circuit means modulating the other electron stream, said two circuit means having different frequencies.
4. A discharge device including a hollow body 70 resonator and means symmetrically disposed to said resonator for applying two different frequencies of the order of megacycles to said hollow body resonator.
5. A discharge device including a hollow body 75

resonator and means for applying two different frequencies to said hollow body resonator, said hollow body resonator having an output circuit having two branches, one branch tuned to one of said frequencies, the other branch tuned to the other frequency.

6. A discharge device including a hollow body resonator and means for applying two different frequencies to said hollow body resonator, said hollow body resonator having an output circuit having two branches, one branch tuned to one of said frequencies, the other branch tuned to the other frequency, a circuit coupled to the branches of said output circuit, said circuit being tuned to the beat frequency of said two frequencies.

7. A discharge device including a hollow body resonator having openings for the passage of electrons therethrough at two different portions of said resonator, cathode means for supplying electrons to the openings at one portion, cathode means for supplying electrons at the other portion, a circuit means modulating one electron stream, another circuit means modulating the other electron stream, said two circuit means having different frequencies, said hollow body resonator having an output circuit having two branches, one branch tuned to one of said frequencies, the other branch tuned to the other frequency.

8. A discharge device including a hollow body resonator having openings for the passage of electrons therethrough at two different portions of said resonator, cathode means for supplying electrons to the openings at one portion, cathode means for supplying electrons at the other portion, a circuit means modulating one electron stream, another circuit means modulating the other electron stream, said two circuit means having different frequencies, said hollow body resonator having an output circuit having two branches, one branch tuned to one of said frequencies, the other branch tuned to the other frequency, a circuit coupled to the branches of said output circuit, said circuit being tuned to the beat frequency of said two frequencies.

9. A discharge device including a hollow body resonator the body whereof provides a resonator chamber having openings common to the one chamber for the passage of electrons therethrough directly into said chamber at two different portions thereof, and two current means at different frequencies for passing electrons through said openings, said current means comprising hollow body resonators tuned respectively to said frequencies.

10. A discharge device including a hollow body resonator the body whereof provides a resonator chamber having openings common to the one chamber for the passage of electrons therethrough directly into said chamber at two different portions thereof, and two current means at different frequencies for passing electrons through said openings, said current means comprising hollow body resonators tuned respectively to said frequencies, and cathode means in each of said last mentioned resonators for producing said electrons.

11. A discharge device including a hollow body resonator having openings for the passage of electrons therethrough at two different portions of said resonator, and two current means at different frequencies for passing electrons through said openings, said current means comprising hollow body resonators tuned respectively to said frequencies, said first mentioned hollow body reso-

nator having an output circuit having two branches, one branch tuned to one of said frequencies, the other branch tuned to the other frequency.

12. A discharge device including a hollow body resonator having openings for the passage of electrons therethrough at two different portions of said resonator, and two current means at different frequencies for passing electrons through said openings, said current means comprising hollow body resonators tuned respectively to said frequencies, said first mentioned hollow body resonator having an output circuit having two branches, one branch tuned to one of said frequencies, the other branch tuned to the other frequency, a circuit coupled to the branches of said output circuit, said circuit being tuned to the beat frequency of said two frequencies.

13. In combination, a main hollow body resonator, a second and a third auxiliary hollow body resonators, means for applying to said second and third hollow body resonators different high frequencies oscillations, each of said second and third hollow body resonators being tuned to the frequency applied thereto, and means for passing electron streams from each of said second and third hollow body resonators to said main hollow body resonator, said electron streams being modulated by said frequencies.

14. In combination, a main hollow body resonator, a second and a third auxiliary hollow body resonators, means for applying to said second and third hollow body resonators different high frequencies oscillations, each of said second and third hollow body resonators being tuned to the frequency applied thereto, and means for passing electron streams from each of said second and third hollow body resonators to said main hollow body resonator, said electron streams being modulated by said frequencies, said hollow body resonator having an output circuit having two branches, one branch tuned to one of said frequencies, the other branch tuned to the other frequency.

15. In combination, a main hollow body resonator, a second and third auxiliary hollow body resonators, means for applying to said second and third hollow body resonators different high frequencies oscillations, each of said second and third hollow body resonators being tuned to the frequency applied thereto, and means for passing electron streams from each of said second and third hollow body resonators to said main hollow body resonator, said electron streams being modulated by said frequencies, said hollow body resonator having an output circuit having two branches, one branch tuned to one of said frequencies, the other branch tuned to the other frequency, a circuit coupled to the branches of said output circuit, said output circuit being tuned to the beat frequency of said two frequencies.

16. An ultra high frequency oscillator comprising a first hollow body resonator, a second hollow body resonator, a cathode within said first hollow body resonator, passage means for said electrons from said first hollow body resonator to the second hollow body resonator, said second body resonator receiving said electrons when its field is in opposition to the passage of electrons therein whereby said electrons give up energy to said second hollow body resonator, said cathode being located next one part of the resonator and having metal capacitative means connected symmetrically therewith at an opposite part of the resonator, whereby the capacity between said cathode

and said first hollow body resonator is substantially symmetrically distributed within said body.

17. An ultra high frequency oscillator comprising a first hollow body resonator, a second hollow body resonator, a cathode within said first hollow body resonator, passage means for said electrons from said first hollow body resonator to the second hollow body resonator, said second body resonator receiving said electrons when its field is in opposition to the passage of electrons therein whereby said electrons give up energy to said second hollow body resonator, the cathode within said first hollow body resonator being an elongated structure having opposite ends and providing lumped capacity between said ends and the said enclosing hollow body resonator.

18. The method of producing oscillations in a resonator common to two electron streams which

comprises separately producing two electron streams, applying high frequency currents of different frequencies to said streams while separate, thereby modulating each electron stream, and feeding the modulated electron streams to said resonator common to both streams.

19. The method of producing oscillations in a resonator common to two electron streams which comprises producing two electron streams, applying high frequency currents of different frequencies to said streams while separate, thereby modulating each electron stream, feeding the modulated electron streams to said resonator common to both streams and producing a beat frequency, and carrying off the beat frequency as the output of produced oscillations.
